O. A. HILL, OF WESTBROOK, MAINE.

Letters Patent No. 87,566, dated March 9, 1869.

IMPROVEMENT IN BRIDGES FOR PLAYING POOL.

The Schedule referred to in these Letters Patent and making part of the same.

To all whom it may concern:

Be it known that I, O. A. HILL, of Westbrook, in the county of Cumberland, and State of Maine, have invented a new and useful Improved Pool-Bridge; and I hereby declare the following to be a full, clear, and exact description thereof, which will enable others to make and use my invention, reference being had to the accompanying drawings, forming part of this specification, in which—

Figure 1 is an end elevation of my improvement.

Figure 2 is a side elevation of the same.

This invention relates to that class of articles called bridges, employed on billiard-tables, to form a rest for the cue when the player's ball is too remote from any position he can take around the table, for forming the bridge by his own hand.

These articles are also used to catch and arrange the balls when scattered over the table.

There are other uses to which, if properly constructed, they might be applied, and subserve a very useful and convenient purpose.

In the game of pool, where small pins are placed on the table, as these are thrown down by the balls, they are apt to be thrown or to roll under the shelving cushions or banks of the table, and then the players must pick up each pin by hand. If, however, there were an instrument so devised as to fit under the shelving cushions or banks of the table, the pins could be easily raked together, at the centre of the board, without trouble, and replaced as the order of the games required. This cannot be done by the ordinary bridge as now constructed.

I propose to effect this by the projecting sides *a a*,

which allow the bridge to be drawn along, touching the bank, and extending under the same.

b shows the arrangement for using the bridge as an ordinary one.

c, the arrangements for resting the cue when the bridge is turned upon end, as is often necessary.

In the common bridge, as now used, the blade is at right angles to the stem, or handle *d*.

As seen in fig. 2, I arrange these at a certain inclination to each other, in order to the more convenient use of the bridge to collect balls over the table, and the sliding of the blade along the table.

The blade can be made of any useful material, as wood, gutta-percha, or other material.

On the bottom of the blade, at *e*, are curved places, cut up into the said blade a short distance. This is to make the friction on the table less, and to aid in catching and drawing along a pin if the blade should strike on one, instead of behind it. If the blade were even on the bottom, it would slip over the pin, but with the scallops, the pin will slip into one of them, and so be drawn along with the bridge.

Particles of dirt, &c., can be removed from under the cushions by the bridge made as herein shown, that is, so as to extend under the same.

What I claim as my invention, and desire to secure by Letters Patent, is—

The improved pool-bridge, as herein shown and described.

O. A. HILL.
